UNITED STATES PATENT OFFICE.

ANDREW L. RIKER, OF NEW YORK, N. Y., ASSIGNOR, BY MESNE ASSIGNMENTS, TO ELECTRIC VEHICLE COMPANY, OF JERSEY CITY, NEW JERSEY, AND HARTFORD, CONNECTICUT, A CORPORATION OF NEW JERSEY.

ELECTRIC IGNITER FOR EXPLOSIVE-ENGINES.

SPECIFICATION forming part of Letters Patent No. 734,138, dated July 21, 1903.

Application filed January 8, 1900. Serial No. 769. (No model.)

To all whom it may concern:

Be it known that I, ANDREW L. RIKER, a citizen of the United States, and a resident of the city of New York, State of New York, have 5 invented a new and useful Electric Igniter for Explosive-Engines, which is fully set forth in the following specification.

My invention relates to electric-spark igniters for explosive-engines; and it consists, 10 essentially, of a vibratory interrupter that comprises a fixed terminal and a movable terminal constructed and mounted to vibrate freely back and forth and a cam or other device operated by the engine for plucking the 15 movable member.

The invention consists, further, in providing for adjustment of the sparking period relatively in the cycle of the engine.

It is essential in explosive-engines that a 20 spark be produced without fail when needed, and to this end the making and the breaking of contacts in the electric circuit should each be as instantaneous as possible, which I accomplish by producing both the makes and 25 the breaks by spring action. To insure the desired result without fail, this same spring action produces a series of instantaneous and immediately-successive (spring action) makes and breaks. Further, my device is arranged 30 to be operated when the engine-shaft is rotated in either direction, forward or backward, and, finally, the various parts are mounted on a radially-adjustable plate to permit the adjustment of the sparking period 35 relatively in the cycle of the engine.

The drawing annexed hereto as part of this application is a diagrammatic view showing my invention.

On a shaft A, driven by the engine, is a 40 rounded crank arm or projection A', constituting a convex cam-surface. B is a plate mounted on this shaft and radially adjustable thereon, as by mechanism B', similar to a brake-lever and rack. On this plate, as at 45 C, is mounted a properly-insulated spring-arm D, so arranged that it can vibrate freely back and forth or is, as must be seen, nor-

mally inert, at least to such extent and for the purpose as herein indicated. At its lower end is a head d, which the cam A' acts upon 50 to pluck the spring-arm. This arm D is preferably so arranged that shaft A lies in the line of its prolongation, so that whether the engine rotates this shaft to the right or to the left in either case cam A' serves to pluck the 55 head d and throw the arm into vibrations. At one side on plate B is a lug E, in which is mounted a properly-insulated set-screw F, whose end f (preferably of platinum) constitutes the relatively fixed terminal or contact-point of the main circuit. On spring-arm D, opposite screw F, is a block d', (also platinum by preference,) that constitutes the relatively movable terminal or contact-point of the main circuit. This main circuit em- 65 braces a battery G, a condenser G' connected therewith, and a transformer H. The ends of the wire composing the circuit are connected to terminals d' and f, respectively, so that the circuit is closed only when the terminals are in contact. A secondary circuit from transformer H has the sparking-termi- 70 nals I properly located in an explosion-chamber.

The operation of the device is as follows: 75 As the shaft rotates, which may be in either direction, the cam moves the end of spring-arm D until the latter can escape, when its spring action throws it back, setting it into true to-and-fro vibrations. Terminal d' is 80 brought into instantaneous contact with terminal f and is as instantaneously drawn away, and this is repeated a number of times. This rapid vibration of the spring-arm produces a rapid succession or series of quick sharp 85 blows and a consequent series of instantaneous and immediately-successive interruptions or makes and breaks in the main circuit, thereby producing an unfailing spark or series of sparks in the secondary circuit at I. 90 It will be noted in addition to producing a series of interruptions that both the making and the breaking of the contact between the terminals in the interrupter are produced by

spring action—that is, they are quicker and more instantaneous than if produced by the comparatively slow mechanical moving or lifting of one terminal against or away from the other—and, further, that my interrupter can be operated regardless of the direction in which the engine-shaft is rotated. In case it be desired to have the sparking take place at a different period in the cycle of the engine, proper manipulation of lever B' shifts the plate B and the operative parts carried thereby, so that the cam A' will act on head d either a little sooner or a little later than before. This may be done while the engine is running.

I do not limit myself to the arrangement of parts indicated or to the exact construction disclosed. The spirit of my invention lies in the employment of a freely-vibrated terminal as one member of the interrupter of the main circuit and in thereby producing a succession of vibrations and of spring-action makes and breaks for each time the movable terminal is plucked.

Having thus described my invention, I claim—

In combination in an igniter for explosive-engines, an electric circuit, an interrupter comprising a fixed terminal, a freely-vibrating spring-arm carrying the movable terminal, a cam rotated in unison with the engine, said cam located in the line of prolongation of said spring-arm when in its normal position and having similar opposed faces whereby said spring-arm will be plucked out of its normal position by a rotation of said cam in either direction, said fixed contact and spring-arm being mounted on a member angularly adjustable around the cam-center, all substantially as and for the purpose described. 40

In testimony whereof I have signed this specification in the presence of two subscribing witnesses.

ANDREW L. RIKER.
